UNITED STATES PATENT OFFICE.

ALEXANDER E. BROWN, OF CLEVELAND, OHIO, ASSIGNOR TO THE BROWN HOISTING MACHINERY COMPANY, OF CLEVELAND, OHIO, A CORPORATION.

GRAB-BUCKET.

SPECIFICATION forming part of Letters Patent No. 723,183, dated March 17, 1903.

Application filed October 13, 1902. Serial No. 127,012. (No model.)

To all whom it may concern:

Be it known that I, ALEXANDER EPHRAIM BROWN, a citizen of the United States, residing at Cleveland, in the county of Cuyahoga and State of Ohio, have invented a new and useful Grab-Bucket for the Automatic Handling of Coal, Ore, and other Material, as to which I hereby declare the following to be a full, clear, and exact description, due reference being had and intended to the several drawings accompanying this specification and which I mean to have considered a part thereof.

Said invention belongs to the general class of buckets for automatically taking up material from stock-piles, whereby the load is gathered and held by bringing together with in the material to be loaded two oppositely-related bucket segments or jaws. A familiar type of this class is the so-called "clam-shell" bucket, whose jaws rotate about a common pivot at their upper ends and when closed make up a semispherical receptacle or bucket proper. In this particular type the line of travel of the blades is a fixed curve, and under the best conditions the quantity grabbed by buckets of this description at each operation is largely determined and limited by the depth of the initial penetration. Inasmuch as the bucket at that moment, with its blades or jaws, is rapidly drawn upward and out of the source of supply, should the penetration not suffice for a load as the jaws begin to close it is not likely that in the passage of the bucket upward the original charge will be increased. In this type of bucket also the material is always carried away in a series of curvilinear cuts or scoops, and such buckets therefore are not adapted to clean up the corners of a receptacle or to pick up material anywhere when the lowest depth of such material is reached. At the final stages, therefore, of the process of unloading barges, bins, or docks their work must always be supplemented by hand. In all buckets of the general class referred to, including, of course, the particular type just mentioned, by reason of the necessity, on the principle of their designs of making the opposite jaws close against each other, not only along the cutting or scraping edges, but along the upright

sides of said jaws, the jaws themselves are impaired in their efficiency as scraping or scooping instruments. Because of the need just referred to, due to their dual character of bucket-halves and bucket segments or jaws, each bucket segment or jaw must carry in advance of and at right angles to the bucket's scooping-surfaces the portion or parts that are to form the bucket's sides when the jaws are closed. In the operation of closing, however, these often interfere with an effective filling, because should embedded lumps of coal or ore or boulders in earth-excavities be encountered by these portions or parts on the jaws that are to constitute the bucket's sides when the jaws are closed, as aforesaid, the scraping edge proper of the jaws will thereby be raised in or out of the stock-pile, much as, for instance, a sled-body would be carried from the normal should one of its runners or shoes encounter an obstacle.

It is the purpose and object of my present invention to provide an effective instrument of the class specified whose principle of construction and operation combines and utilizes to the best advantage both the dipping or scooping features referred to and a desirable scraping movement of the jaws when in contact with the material to be loaded, and, furthermore and to an eminent degree, provides the necessary sides for the bucket proper without the undesirable features last described. By reason of this characterization the bucket I have invented is adapted to fill itself with material without regard to whether such is located either in corners or on flat surfaces and however slight its depth may be and to retain whatever material is once grabbed without spilling or loss. At the same time said bucket is rapid and simple in action, is not liable to fail of a load by reason of encountering gross obstacles, and is designed to meet all strains that its work involves.

In the accompanying drawings, Figure I is a side elevation of a complete bucket comprehending my said invention. Fig. II is a vertical longitudinal sectional view of the bucket when closed, with dotted lines indicating the path of its jaws from an open to a closed position. Fig. III is a similar view of

the bucket when open. Fig. IV is a vertical sectional view on the line 4 4 of Fig. I in the direction of the arrow. Fig. V is a horizontal sectional view downward on the line 5 5 of Fig. II. Fig. VI is a similar sectional view on the line 6 6 of Fig. II. Fig. VII is an enlarged detached section on the line 7 7 of Fig. II.

Similar reference characters are used on the same parts throughout the drawings.

B is the bucket as a whole. It is made up of an exterior housing or frame H, flaring at its lower portion to the front and rear and having downwardly-projecting side pieces S and S', as indicated and as hereinafter more fully described. Along the bottom of the sides of said housing H, both within and without the same, is securely fastened a rail or track T, upon which are hung sliding blocks or pieces b b, pivotally connected with the forward portion of the jaws or bucket-segments J J, at each side thereof. The jaws J J are composed of two parallel sides p p, joined at their outer ends by a blade-like part D D, which is set at a sharp outward pitch or angle to the vertical through its lower or cutting edge. The parallel sides p p, however, especially in an important application of my present invention claimed herein, are cut away and recede upwardly from the lower or scraping edges of the blade-like parts D D toward and to their upper ends, so that when the jaws J J are brought together and the bucket thereby closed a certain relatively limited portion of the bucket's sides will thereby be made up, and a considerable open space or aperture between the opposing sides of the bucket segments or jaws will exist. The purpose of thus designing said sides p p so that they recede upwardly, as shown and described, is of course to reduce to a minimum or remove entirely from the form of bucket segments or jaws needed in an automatic implement of the kind in question such portions or parts of the same which, though desirable to complete the bucket proper when its constituting jaws are closed, nevertheless essentially interfere with its filling function. In the form shown in the drawings the front and rear of said jaws are preferably uninclosed and extend out beyond the housing H when opened to their outward limit. The sides p p are shown as stiffened by the cross-pieces and diagonal ties e e.

Centrally within the housing H, I locate a block or head C, carrying a series of sheaves M M, mounted upon a common journal or shaft j, transversely seated in the framework of said head or block. At its opposite ends the said head or block is provided with trunnions t t, adapted to register and be in engagement with vertical guides or grooves g g, located on the opposite interior sides of the housing H for the purpose. Said grooves g g extend up and down the said housing and at their lowest limits have stops d d, adapted to be encountered by the trunnions t t when at

such points in their downward movement. Said trunnions in the specific construction illustrated are utilized as pivotal bearings or journals for the inner ends of sides p p of the jaws J J, which are connected thereto accordingly. At the top of the housing H is located a second block or head E, containing another series of sheaves M' M', which in the construction illustrated are one less in number than the sheaves of the lower block or head C. The sheaves in said blocks or heads C and E are set at such angles with relation to each other that the planes of any pair of strands of the operating-rope reeved around the same shall be at right angles to the axis of said sheaves. With respect to the center line of the bucket's top said sheaves are given such an angle that the onrunning and offrunning portion of the operating-rope shall come on the center line of said bucket's top. Rope guides or eyes m n are provided on opposite sides of the block or head E, with centers corresponding with the center line of the bucket B. Hinged to the block or head E is the hoisting-block G, having rope guides or eyes m' n' at either side registering with the guides or eyes m n on the block E.

O is the operating-rope whereby the bucket is closed or allowed to open. It passes downward through the eye m' n' around a sheave in the lower block or head C, thence upwardly around a corresponding sheave in the upper block or head E, down around the next adjacent sheave in the block C, and so on around any remaining sheaves in said heads until its reeving among them is completed, when the outgoing portion of said rope is carried up through the eyes n and n' to the hoisting mechanism.

R is the hoisting-rope, which is reeved about the hoist-block G and connected with the source of power in the usual manner.

Being constructed and equipped in the manner above pointed out, said bucket is operated by lowering the same above the material from which it is to derive its load by paying out both the hoisting and the operating ropes. When in proximity to said material, the hoisting-rope is held taut and the operating-rope O is slackened. The block or head C being thus freed, will, by reason of its weight, descend within the housing H, being guided vertically by the said trunnion-grooves and at the same time carrying with it and depressing the pivoted inner ends of the jaws J J. It is evident that by this movement the said jaws, being pivotally connected near their outer ends to the sliding blocks or pieces b and b, mounted on the tracks or guides T, said blocks will be forced outwardly along said tracks and carry with them the outer ends of said jaws J and the bucket thereby opened. The contour of said track T is such that, in connection with the vertical movement of the head C, the blades D D of the jaws J in their course in opening and closing may be constrained to describe any desired

curve or course within the bucket's limits—such, for instance, as that indicated by the dotted lines in Fig. II. In practice, particularly where material is to be taken from flat surfaces or from against the sides of a bin or barge, the path of the scraping edge of the blade-like part D should at the initial movement of closing descend with a sharp curvature that diminishes as the jaws approach each other, whereby the material is first penetrated to a depth to insure a purchase and load and is then scraped together within the bucket. As the drawings indicate, the downwardly-projecting pieces S S' serve to prevent the escape of material at the sides when the jaws are closed, and by leaving the rear of said jaws uninclosed, as I preferentially do, any surplus load above the capacity of the bucket will be forced out at the rear without in any degree packing within the bucket or interfering with its proper operation. Said side or downwardly-extending pieces s' are essential features of my device in the form thereof covered by the special claims referring to the same. Indeed, whatever the form of bucket in other respects such side pieces are material adjuncts in the successful use of any bucket having hoe-shaped jaws that have sides which are cut away in front of the lower or scraping end and recede upwardly therefrom or are omitted entirely.

Of course many modifications of the construction above described may be made in design or detail without departing from my invention in its broader scope, and in this sense I accordingly do not wish that said invention be limited to the precise forms I show. The method of movably connecting the jaws to the track T, for instance, or supplying its function may be varied and changed and a bucket bearing such changed feature would still come within the wider principle I intend to cover and claim, and although in showing an operative device that includes the principles of my invention I have represented the sheave-block C with an axis coincident with that of the pivotal connection of the bucket segments or jaws D, I do not intend in every instance to limit my invention to that precise relation between said head or sheave block and the pivotal point of said jaws. As a matter of useful construction it will often be found of advantage to connect said sheave-blocks to the common pivotal point of said jaws in such manner that the head or block carrying the sheaves does not share the common pivot or pivotal point, but, on the contrary, is located above or elsewhere therefrom. So, too, while I have described and shown a bucket whose jaws by virtue of the particular contour of the guides or tracks carrying the sliding blocks or pieces b are constrained to travel in such manner that the lower or scraping edges of said jaws describe a diminishing curve I do not mean in the broader sense to confine said contour to that so shown. My invention comprises any predetermined

contour for said guides or tracks, and they may in consequence be so varied as to correspondingly vary the path of said edges and without departing from my invention, as set out in certain of the claims, to accordingly make said edges describe a regular curve, for instance, or to move entirely in a straight line or lines.

What I claim as new, and desire to secure by Letters Patent, is—

1. In a hoisting-bucket, the combination, with a housing or framework of bucket segments or jaws, oppositely hinged or pivotally joined together within the same at their upper ends, and pivotally connected to said housing or framework near their lower ends by movable fulcrums; guides or tracks on said housing or framework upon which said fulcrums bear, and suitable means for vertically raising said upper ends of said segments or jaws within said housing, and of permitting the same to similarly descend, substantially as shown and described. 75

2. In a hoisting-bucket, the combination, with a housing or framework of bucket segments or jaws, with upwardly-receding sides oppositely hinged or pivotally joined together with the same at their upper ends, and pivotally connected to said housing or framework near their lower ends by movable fulcrums; guides or tracks on said housing or framework upon which said fulcrums bear, and suitable means for vertically raising said upper ends of said segments or jaws within said housing—and of permitting the same to similarly descend—substantially as shown and described. 90

3. In a hoisting-bucket, the combination, with a housing or framework of bucket segments or jaws, with upwardly-receding sides, oppositely hinged or pivotally joined together within the same at their upper ends, and pivotally connected to said housing or framework near their lower ends by movable fulcrums; guides or tracks on said housing or framework upon which said fulcrums bear, side pieces extending downwardly from said housing or framework suitably located and of proper dimensions to close the aperture or space between said segments or jaws when the latter are in contact at their lower or scraping edges, and suitable means for vertically raising said upper ends of said segments or jaws within said housing—and of permitting the same to similarly descend—substantially as shown and described. 105

4. A hoisting or grab bucket, having two jaws pivotally connected together at their upper ends within a housing provided for the purpose, and pivotally connected near their lower ends to said housing by movable connections arranged to follow a predetermined course when said upper ends are vertically oscillated within said housing, in combination with suitable means for so oscillating said upper ends, substantially as shown and described. 125 130

5. A hoisting or grab bucket, having two jaws with upwardly-receding sides, pivotally connected together at their upper ends within a housing provided for the purpose, and pivotally connected near their lower ends to said housing by movable connections arranged to follow a predetermined course when said upper ends are vertically oscillated within said housing, in combination with suitable means for so oscillating said upper ends, substantially as shown and described.

6. A hoisting or grab bucket, having two jaws with upwardly-receding sides, pivotally connected together at their upper ends within a housing provided for the purpose, and pivotally connected near their lower ends to said housing by movable connections, arranged to follow a predetermined course when said upper ends are vertically oscillated within said housing, side pieces extending downwardly from said housing suitably located and of proper dimensions to close the aperture or space between said segments or jaws when the latter are in contact at their lower or scraping edges, in combination with suitable means for so oscillating said upper ends, substantially as shown and described.

7. A hoisting or grab bucket, having two jaws pivotally joined together at their upper ends within a housing provided for the purpose, a sheave-block connected to said pivotal coupling of said jaws, and vertical guides for said sheave-block through said housing; guides or tracks along the lower portion of said housing carrying sliding blocks or pieces to which said jaws are pivotally connected, the said guides or tracks having a predetermined contour according to which, when said head is vertically oscillated, said blocks or pieces, with their connected jaws, will be constrained to travel and to thereby shift said fulcrums or pivotal points near the lower ends of said jaws, in combination with suitable means for oscillating said head, substantially as shown and described.

8. A hoisting or grab bucket, having two jaws with upwardly-receding sides pivotally joined together at their upper ends within a housing provided for the purpose, a sheave-block connected to said pivotal coupling of said jaws, and vertical guides for said sheave-block through said housing; guides or tracks along the lower portion of said housing carrying sliding blocks or pieces to which said jaws are pivotally connected, the said guides or tracks having a predetermined contour according to which, when said head is vertically oscillated, said blocks or pieces, with their connected jaws, will be constrained to travel and to thereby shift said fulcrums or pivotal points near the lower ends of said jaws, in combination with suitable means for oscillating said head, substantially as shown and described.

9. A hoisting or grab bucket, having two jaws with upwardly-receding sides pivotally joined together at their upper ends within a

housing provided for the purpose, side pieces extending downwardly from said housing suitably located and of proper dimensions to close the aperture or space between said segments or jaws, when the latter are in contact at their lower or scraping edges, a sheave-block connected to said pivotal coupling or connection of said jaws, and vertical guides for said head through said housing; guides or tracks along the lower portion of said housing carrying sliding blocks or pieces to which said jaws are pivotally connected, the said guides or tracks having a predetermined contour according to which, when said head is vertically oscillated, said blocks or pieces, with their connected jaws, will be constrained to travel and to thereby shift said fulcrum or pivotal points near the lower ends of said jaws, in combination with suitable means for oscillating said head, substantially as shown and described.

10. In a hoisting-bucket, the combination of two jaws pivotally connected together within a framework provided for the purpose, the said pivotal connection being connected, at or near the same with a series of sheaves and being in engagement with guides or tracks along the lower portion of said framework provided with movable blocks or pieces to which said jaws are pivotally connected near their ends; a head or block at or near the top of said bucket containing a series of sheaves corresponding with those hereinbefore first described, together with an operating rope or chain suitably reeved around said two series, substantially as shown and described.

11. In a hoisting-bucket, the combination of two jaws with upwardly-receding sides pivotally connected together within a framework provided for the purpose, the said pivotal connection being connected, at or near the same, with a series of sheaves and being in engagement with guides or tracks extending vertically through said framework; guides or tracks along the lower portion of said framework provided with movable blocks or pieces to which said jaws are pivotally connected near their lower ends; a head or block, at or near the top of said bucket containing a series of sheaves corresponding with those hereinbefore first described, together with an operating rope or chain suitably reeved around said two series, substantially as shown and described.

12. In a hoisting-bucket, the combination of two jaws with upwardly-receding sides pivotally connected together within a framework provided for the purpose, the said pivotal connection being connected with a series of sheaves provided for the purpose and being in engagement with guides or tracks extending vertically through said framework; guides or tracks along the lower portion of said framework provided with movable blocks or pieces to which said jaws are pivotally connected near their lower ends; side pieces extending downwardly from said framework of

- suitable dimensions to close the aperture or space between said jaws when the latter are in contact at their lower or scraping edges; a head or block, at or near the top of said bucket 5 containing a series of sheaves corresponding with those hereinbefore first described, together with an operating rope or chain suitably reeved around said two series, substantially as shown and described.
13. In a hoisting-bucket, the combination of two jaws pivotally connected together within a framework provided for the purpose, the said pivotal connection being joined to a series of sheaves provided for the purpose and being in engagement with guides or tracks extending vertically through said framework; guides or tracks along the lower portion of
- said framework provided with movable blocks or pieces to which said jaws are pivotally connected near their lower ends; side pieces extending downwardly from said framework of suitable dimensions to close the aperture or space between said jaws when the latter are in contact at their lower or scraping edges, a head or block at or near the top of said bucket 20 containing a series of sheaves corresponding with those hereinbefore first described, together with an operating rope or chain suitably reeved around said two series, substantially as shown and described.
15. 13. In a hoisting-bucket, the combination of two jaws pivotally connected together within a framework provided for the purpose, the said pivotal connection being joined to a series of sheaves provided for the purpose and being in engagement with guides or tracks extending vertically through said framework; guides or tracks along the lower portion of

ALEXANDER E. BROWN.
